HYDRAULIC LIFTING JACK

Frank Curtis, Seattle, Wash.

Application April 29, 1946, Serial No. 665,778

3. Claims. (Cl. 254—93)

1

This invention relates to lifting jacks and it has reference more particularly to hydraulic jacks of a type especially adapted for house lifting operations and for various analogous uses.

It is the principal object of this invention to provide a jack having a substantial lifting range; which is extremely powerful and is so designed as to insure maximum stability when used with supporting cribbing. Furthermore to provide a jack which embodies therein a hydraulic cylinder from which a lifting piston rod extends and wherein the cylinder has a base for its support that is fixed thereto adjacent that end from which the rod extends as differentiated from the usual hydraulic or screw jack design having a flared base at the end of the jack body or cylinder opposite that from which the piston rod or screw extends.

It is also an object of this invention to provide a hydraulic jack comprising a jack cylinder and a piston rod extended from one end thereof and a supporting base for the cylinder fixed about the upper end of the cylinder and which base is hollow and serves also as the reservoir for the hydraulic medium and as a support or mounting for a hand operated pump mechanism whereby the hydraulic pressure medium may be forced into the cylinder for the extending of the jack.

It is also an object of this invention to provide a hydraulic jack that is especially adapted for heavy commercial lifting operations, that is easy to mount, convenient to use, compact in design, powerful in its lifting function, that can be quickly retracted and which provides both for precision lifting or lowering.

Still another object of the invention is to provide a jack of the kind above stated that may be used in vertical or horizontal position, and for various power applying operations.

Other objects of the invention reside in the details of construction and combination of its parts and the mode of use of the jack as will herein-after be fully described.

In accomplishing the above mentioned and other objects of the invention, I have provided the improved details of construction, the preferred forms of which are illustrated in the accompanying drawings, wherein—

Fig. 1 is a view showing partially in elevation and partially in longitudinal section, a jack mechanism embodied by the present invention.

Fig. 2 is a sectional detail of an alternative form of power pump mechanism adapted for use with jacks of the present kind.

Fig. 3 is a top, or plan view of the jack as supported by cribbing for use.

2

Fig. 4 is a horizontal cross section taken on line 4—4 in Fig. 1.

Fig. 5 is an elevation showing one way of mounting the jack for use.

Referring more in detail to the drawings—

The present jack in one of its forms of construction comprises a hydraulic cylinder 10, shown in Fig. 1 as being closed at its lower end by a plug 11 that is threaded and welded in the end of the cylinder body. Reciprocally contained in the cylinder and extending from its upper end is a piston rod 12 having a suitable head packing or gasket, as at 13, at its lower end. The packing washer is here shown as being held in place by an overlying washer 14 and a nut 15, that are applied to a stud 16 that extends from the lower end of the rod and through the packing, and washer as seen in Fig. 1.

At its upper end, the piston rod 12 passes through a packed gland 18 that is threaded into the upper end of the cylinder. It is shown also in Fig. 1 that there is slight clearance between the rod and cylinder wall for escape of hydraulic medium that may be forced past the packing 13, as presently explained.

Secured solidly to the upper end portion of the cylinder and extending in a plane perpendicular to the cylinder axis is the supporting base or mounting member, for the jack. This base is designated in its entirety by reference character 20, and it is fabricated of sheet metal plates or might be cast of metal. In plan as noted in Fig. 3, this base is substantially square and the jack cylinder passes centrally therethrough and is fixed solidly thereto. As shown best in Fig. 1, the jack cylinder has a circumferential shoulder 21 about its upper end against which the base engages, and the lower wall of this base is welded, as at 22 to the jack cylinder.

It is shown in Fig. 1 that the base 20 is hollow, thereby forming a reservoir 23 for a supply of hydraulic pressure medium as indicated at 25. This base is here shown as being in the shape of a truncated pyramid, with a flat bottom surface that extends substantially to all sides of the cylinder, thus providing that the jack may be substantially mounted on cribbing blocks, as shown in Fig. 5, giving adequate support for the jack and reducing to considerable extent the distance between the plane of support and the point of contact with the load to be lifted, thereby insuring a minimum tendency of the jack to tip sideways under heavy lifting pressure.

I have here shown the jack piston as being equipped at its upper end with a socket 26 con-

taining a ball bearing 27 against which a socketed bearing plate 28 engages, and which plate would engage the object to be lifted.

To effect the extending of the piston rod for lifting a load, I have provided the jack with a hydraulic pump mechanism as shown best in Fig. 1, this comprising a block or housing 30 that is fixed to the under side of the base member 20 at one side of the cylinder, as best shown in Fig. 1. Formed in this block and extending upwardly therefrom and through the top wall of the base, is a pump cylinder 31 in which a pump piston rod 32 is reciprocally mounted.

Also formed in the block, and opening at its upper end into the supply chambers 23 for the hydraulic pressure medium, is a channel 33 which at its lower end leads into a valve chamber 34 which, in turn, opens into the lower end of the pump cylinder 31. Contained in the chamber 34 is a backcheck valve 35 that opens to admit liquid from the supply chamber to the lower end of the pump cylinder, but which closes automatically to prevent any return flow. Also, communicating directly with the lower end of the pump cylinder 31 is a channel 36 that leads from the block into a channel 37 that leads along the outside of the cylinder wall and at its lower end opens into the lower end of the jack cylinder through the plug 11. The channel 36 contains a spring pressed back check valve 38 therein that prevents any return flow of hydraulic medium through the channel.

It is also shown in Fig. 1 that a by-pass channel 40 leads from the chamber 23 to the channel 36 to provide for a quick return of the hydraulic medium from the lower end of the jack cylinder to the supply chamber when quick lowering of the jack pistons is desired, but which by-pass channel is normally closed by a hand operated valve mechanism indicated at 45 in Fig. 1.

This valve mechanism comprises a threaded valve stem 45a adapted to be turned by hand wheel 45b from and against a valve seat 47 at the juncture of the by-pass channel with the channel 36.

At its upper end, the pump piston rod 32 is pivotally connected, as at 48, with a hand lever 49, which lever, in turn, has a bifurcated inner end portion pivotally connected, through linkage 50, with lugs 51 that are fixed on the top wall of the base member. Up and down action of the hand lever 49 will effect a reciprocal action of the pump piston whereby liquid upon upward travel of the rod, will be drawn from the supply chamber through channel 33, past valve 35, into the lower end of the cylinder 31; then when rod 32 is forced downwardly this liquid will be forced through channels 36 and 37 into the lower end of the jack cylinder 10 to effect the lifting of the jack piston rod.

It will be understood that the hand lever may be extended to any practical length in order to obtain a desired leverage. After a load has been lifted by upwardly extending the jack piston, and should it be desired to lower the jack, the valve 35 is opened and the hydraulic medium will be permitted to flow back through the channels 37, 36 and 40 into the supply chamber. For a precision lowering operation, the valve 35 may be adjusted for very slow downward travel of the jack.

It is shown in Fig. 1 also that access to the by pass valve 38 may be had by removal of a plug 60 that is threaded into the block. Also, access to valve 35 is had by removal of a plug

61 that is threaded into a side wall of the plug. In the latter plug, a seat is formed for the back check valve.

It is noted also in Fig. 1 that there is a bleeder port 66 opening through the jack cylinder wall near its upper end into a channel 67 that leads into the supply chamber, permitting any hydraulic medium that may leak past the piston packing 13 to be returned to the supply chamber.

In Fig. 2, I have illustrated an alternative pumping mechanism in which high pressure and low pressure pumps have been incorporated in a block 30a which would correspond to block 30 of the jack of Fig. 1. This block is formed with a pump cylinder 70 of small diameter, and a pump cylinder 71 of larger diameter; the cylinders contain pump pistons 72 and 73, respectively, designed to be operated individually by hand lever mechanism as previously described. The pump of larger diameter would be used when the load to be lifted is rather light, and the pump of smaller diameter would be used when the load is extremely heavy. As shown in Fig. 2, both pump cylinders open at their lower ends to a common passage 75 which connects with the lower end of the jack cylinder, in the same manner as channel 36 is connected in Fig. 1, and this connection embodies a back check valve 78 therein corresponding to back check valve 38.

It is shown also in Fig. 2, that the two pump cylinders are supplied both with liquid from chamber 23 through a channel 80 containing a back check valve 81 corresponding to the channel 33 and check valve 35 of Fig. 1. I also provide a hand set valve 90 which may be adjusted to a position to close off the pressure from the high pressure pump to the low pressure pump as a precautionary measure, if such is desired.

As a detail of construction, it is shown in Figs. 1 and 2, that the upper end of channel 33 opens into the chamber within a semi-circular channeled ring 95 extended about the cylinder as in Fig. 2, and which channel is open to the under side of the ring and to a sump 96 in the bottom wall of the chamber. A removable plug 98 is provided in the top wall of the chamber for filling the chamber.

In Fig. 5 I have shown the jack as being supported on cribbing blocks 95 for a direct upward lift of and object designated at 96. In some instances, if the object was close to the ground, it might be necessary first to dig a hole to contain the lower end of the jack therein.

It is to be explained further that jacks of this kind can be used in various ways other than illustrated in Fig. 5. Where conditions are satisfactory and the load light the lower end of the jack cylinder might be set directly upon a support.

If it should be found desirable, the jack could be used in a horizontal position, for pushing or even in an inverted position for lifting.

Jacks of this character may be made in various sizes and equipped with the single or dual pump mechanism.

One of the principal advantages of the present construction and arrangement is thought to reside in the relationship of the supporting base structure to the jack cylinder and in the utilization of this hollow base as a reservoir or chamber for the hydraulic pressure medium. The placing of the base close to the upper end of the jack gives stability to the jack in use, and furthermore permits the lower end portion of the jack to be placed in a hole if such should be re-

quired in order to lower the jack sufficiently to get under the object being lifted.

Insofar as the advantages of placing the base near the upper end of the jack cylinder are concerned, this same construction is applicable to jacks of other types; for example, the well-known type of screw jack, and it is not desired that insofar as claims to this part are concerned, that they be restricted to hydraulic jacks but that they shall be applicable to any jack where the lifting shaft or piston is extendable from a mounting house.

Having thus described my invention, what I claim as new therein and desire to secure by Letters Patent is:

1. A jack of the character described comprising a hydraulic jack cylinder of substantial length, a piston operatively fitted in the cylinder and extended from the upper end thereof to engage the object to be lifted and terminating substantially flush therewith when fully lowered, a supporting base for the jack in the form of a hollow flange and affixed rigidly to the cylinder about that end portion from which the piston extends and having a chamber of substantial volume therein for a supply of hydraulic pressure medium, and a pump mechanism mounted on the jack and operable to deliver hydraulic pressure medium from the said chamber into the cylinder to extend the piston in a lifting operation.

2. A jack of the character described comprising a hydraulic jack cylinder of substantial length, a piston operatively fitted in the cylinder and extended from an end thereof to engage the object to be lifted, a supporting base for the jack in the form of a hollow flange affixed to the cylinder about that end portion from which the piston extends and extending to all sides

thereof and having a chamber therein for a supply of hydraulic pressure medium, and a pump mechanism mounted on the jack base and operable to deliver hydraulic pressure medium from the said chamber into the cylinder to extend the piston in a lifting operation, and there being a channel in said pump mechanism for return flow of the hydraulic medium from the jack cylinder to the chamber, and an adjustable valve for controlling the rate of return flow of liquid therethrough.

3. A jack of the character described comprising a hydraulic jack cylinder, a piston operatively fitted in the cylinder and extended from an end thereof to engage the object to be lifted, a supporting base for the jack surrounding the cylinder about that end portion from which the piston extends and having a support engaging surface that is perpendicular to the axis of the cylinder and a chamber therein for a supply of hydraulic pressure medium, and a pump mechanism mounted on the jack and operable to deliver hydraulic pressure medium from the said chamber into the cylinder to extend the piston in a lifting operation, and means on the said base for the manual actuation and control of the lifting element.
